UNITED STATES PATENT OFFICE

119,051

DESIGN FOR AN AIR CONDITIONING UNIT

Thomas Landseer Campbell Rogers, London,
Ontario, Canada

Application October 2, 1939, Serial No. 87,477

Term of patent 7 years

To all whom it may concern:

Be it known that I, Thomas Landseer Campbell Rogers, a subject of Great Britain, residing at London, Ontario, Canada, have invented a new, original, and ornamental Design for an Air Conditioning Unit, of which the following is a specification, reference being had to the accompanying drawing forming part thereof.

Figure 1 is a perspective view of an air conditioning unit showing my new design; and

Figure 2 is a plan view of the unit.

The side and end of the unit not shown in the drawing are substantially plain.

I claim:

The ornamental design for an air conditioning unit, as shown and described.

THOMAS LANDSEER
CAMPBELL ROGERS.
